CLAIM

The ornamental design for a grooming tool, as shown and described.

DESCRIPTION

FIG. 1 is a top, right, front perspective view of an embodiment of a grooming tool, according to the new design; FIG. 2 is a bottom, right, rear perspective view of the grooming tool of FIG. 1; FIG. 3 is a front view of the grooming tool of FIG. 1; FIG. 4 is a rear view of the grooming tool of FIG. 1; FIG. 5 is right side view of the grooming tool of FIG. 1; FIG. 6 is a left side view of the grooming tool of FIG. 1; FIG. 7 is a top view of the grooming tool of FIG. 1; and, FIG. 8 is a bottom view of the grooming tool of FIG. 1. The entire exemplary broken line showing of a head component that is illustrated beyond the neck portion of the grooming tool handle, comprising a combing blade, head and retained tool, is depicted illustratively only, and forms no part of the claimed design.
